FIRING MECHANISM FOR AUTOMATIC FIREARMS

Marriner A. Browning, Ogden, Utah, assignor to
 J. M. & M. S. Browning Company, Ogden,
 Utah, a corporation of Utah

Original application April 10, 1934, Serial No.
 719,862. Divided and this application March
 19, 1935, Serial No. 11,792

20 Claims. (Cl. 89—27)

The principal object of the invention is to provide an improved retarding mechanism whereby the gun may be caused to operate at a slower speed than it otherwise would.

5 Another object is to provide a construction whereby the several parts of the firearm may be quickly and easily assembled or disassembled.

A still further object of the invention is to provide a construction whereby movement of the 10 sear into its operative position is of a snap-action character.

This present application constitutes a division of my co-pending application for Automatic firearm, Serial No. 719,862, filed April 10, 1934, which 15 15 said co-pending application was issued as Patent No. 2,093,704 on September 21, 1937.

In the accompanying drawings I have shown the embodiment of the invention which I now deem preferable, but it will be understood that the drawings are intended for illustrative purposes only and are not to be relied upon as limiting or defining the scope of the invention, the claims forming a part of this specification being relied upon for that purpose.

25 Of the drawings:

Fig. 1 is a side view of a firearm embodying the invention.

Fig. 2 is an enlarged fragmentary view of the rear portion of the firearm, this view being partly 30 a side view and partly a longitudinal sectional view.

Fig. 3 is a view similar to Fig. 2 but showing the parts in different relative positions.

Fig. 4 is a fragmentary sectional view taken 35 along the line 4—4 of Fig. 3.

Fig. 5 is a detail view showing an intermediate position to which the action spring yoke is moved during disassembly of the gun.

Fig. 6 is an enlarged plan view of the trigger and retarding mechanism shown in Figs. 1, 2 and 3.

Fig. 7 is a fragmentary view similar to Fig. 6 but showing the parts in different relative positions.

45 Fig. 8 is a fragmentary longitudinal sectional view taken along the line 8—8 of Fig. 6.

Fig. 9 is a longitudinal sectional view taken along the line 9—9 of Fig. 6.

Fig. 10 is a view similar to Fig. 6 but showing the parts adjusted to render the retarding mechanism ineffective.

Fig. 11 is a fragmentary longitudinal sectional view taken along the line 11—11 of Fig. 10.

Fig. 12 is a fragmentary longitudinal sectional 55 view taken along the line 12—12 of Fig. 10.

Fig. 13 is a rear view of the trigger and retarding mechanisms.

Fig. 14 is a view similar to Fig. 13 but showing the parts in different relative positions.

Referring to the drawings, 1 represents as an 5 entirety the main breech casing which is generally rectangular in transverse section. As shown, the casing is formed from a single piece of steel although I do not necessarily limit myself to this integral construction. The portion 1^a of the 10 casing is formed to receive the rear end of a barrel 2. Behind the portion 1^a are two main side walls connected near the center by an integral cross member 1^c. An opening is provided at the front of the cross member 1^c, which opening is 15 normally closed by a pivoted cover 3 held by a releasable latch 3^a. The bottom of the casing is normally closed by separate front and rear plates. The rear of the casing is normally closed by a plate 7 flanged at its sides and having ribs adapted to enter grooves formed in the side walls. A suitable latch serves to normally hold the end plate 7 in place. Carried by the plate 7 at opposite sides thereof are brackets 8 carrying handles 9.

The casing 1 is provided with an integral extension 1^e which extends forward underneath the barrel. This extension is hollow and it serves to engage and retain a piston tube 16. At its forward end the tube 16 is connected with, and supported by, the barrel. Longitudinally movable along the bottom of the main casing is an operating slide 27, this slide being connected with a piston rod 28 and a piston 29 positioned within the piston tube 16. A cylinder 31 is provided in 30 the forward end of the tube 16, and the piston accurately fits the said cylinder. A gas passage extends from the bore of the barrel to the cylinder, to enable the gases of explosion to enter the cylinder and act upon the piston to force it 35 rearward. For returning the slide in the forward direction after having been moved rearward by the piston and piston rod, there is provided an action spring 132.

Extending transversely through the casing below the rear portion of the barrel is a cartridge feed channel 37 adapted for the reception of a cartridge belt such as A. Transversely movable below the feed channel 37 is a feed slide 39, which is actuated by means of the operating slide 27. 50 As shown, the main portion of the feed slide is below the operating slide, and in this case the operating slide has a cam groove in its lower face into which projects a pin carried by the feed slide. The shape of the groove is such that the 55

feed slide is reciprocated transversely as the operating slide reciprocates longitudinally. The feed slide carries a pawl which engages the cartridge belt to bring a new cartridge into a position below the barrel at each actuation of the operating slide.

The firearm is provided with a reciprocating breech bolt 45 which is guided between the side walls of the casing. The breech bolt is operated and controlled by mechanism operated by the slide 27, this mechanism being similar to that disclosed in Patent No. 1,293,022 to John M. Browning. As shown in Fig. 3, the breech bolt 45 is connected with the slide 27 by means of two links 46 and 47 pivotally connected with each other at 48. The link 46 is pivotally connected with the breech bolt at 49 and the link 47 is pivotally connected with the slide at 50. When the slide 27 is in its rear position, as shown in Fig. 3, the two links 46 and 47 are held substantially in alignment in the relative positions shown. A lug 47a on the link 47 engages the link 46 to prevent downward movement beyond the position shown.

When the slide 27 moves forward under the influence of the action spring 132 the two links 46 and 47 and the breech bolt 45 move in unison with it until the breech bolt nearly reaches its forward position, the link 46 being then approximately in register with the opening 1d in the top wall of the casing. At or about the time that the link comes into register with the opening the curved portion 46b of the link 46 engages two cams 51 projecting inward from the respective side walls of the casing. In the drawings only the cam on the left hand side is clearly shown, but it will be understood that there is a similar cam on the right hand side. These cams 51 cooperate with the curved portion 46b of the link 46 to force the link upward into the opening 1d, the rear end portion of the link abutting against the rear wall of the opening, as clearly shown in Fig. 2. In the meantime the slide 27 has continued its forward movement, thus bringing the link 47 into a substantially upright position. With the parts in the position shown and described, the breech bolt is firmly locked in its forward or breeched position and is well adapted to resist the recoil action incident to firing. Following firing the slide 27 is moved rearward by the action of the gases of explosion in the manner already described, the link 47 serving first to draw the link 46 downward out of locking position and then to move the link 46 and also the bolt 45 rearward to the positions shown in Fig. 3.

It will be understood that the breech bolt 45 and the links 46 and 47 are removable with the slide 27 and the rod 28, all of these parts being removable as a unit.

A firearm incorporating the present invention is intended to be used with cartridges having annular grooves in the heads thereof, and the front end of the breech bolt is provided with vertical ribs 52 which cooperate to form a vertical groove for receiving and retaining the heads of the cartridges. When the breech bolt is in its forward position, as shown in Fig. 2, the head of the cartridge which is in central position in the feed channel 37 is vertically below the groove 52 in the front of the breech bolt. For withdrawing the cartridge from the feed channel and lifting it into proper relationship to the breech bolt there is provided an extractor 54. This extractor is provided with a pivot pin 55 which fits a transverse pivot opening in the breech bolt,

the extractor thus moving bodily rearward and forward as the breech bolt moves. The extractor 54 is provided with a transversely extending tooth 56 which is so shaped and positioned as to enter the groove in the cartridge when the breech bolt and the extractor are in their forward positions, as shown in Fig. 2.

A suitable cam mechanism is provided for controlling and guiding the relative movements of the extractor, but as this cam mechanism constitutes no part of the present invention and is fully disclosed in my said application No. 719,862, it is not necessary to include a detailed description of it in this present specification. It is sufficient to say that when the breech bolt moves rearward the extractor moves rearward and upward, causing the cartridge to be extracted and then lifted into alignment with the chamber in the barrel. As the breech bolt returns in the forward direction, the cartridge is inserted into the chamber and the extractor is again moved downward into position to engage another cartridge in the feed channel.

A second extractor 69 is provided for extracting the empty shell from the chamber as the breech bolt moves rearward. This extractor serves in cooperation with the ejector to eject the empty shell from the ejection opening 76 in the right wall of the casing.

Preferably the operating slide 27 and the parts associated therewith are removable from the firearm at the rear thereof. To effect such removal it is necessary first to remove the action spring 132 in the manner to be presently described and to then remove the end plate 7 with the parts carried thereby. The slide is then substantially free to be withdrawn in the rearward direction, except for the fact that the pin on the feed slide must be disengaged from the groove in the operating slide. At the front of the bottom plate 130 there is provided a guide rod 131 which serves to support and guide the action spring 132. The rear end of the rod 131 is seated in a hole in the plate 130 and the forward end of the rod extends through a yoke 133 secured to the piston rod 28. The action spring abuts at the front against the said yoke 133. Through the medium of the yoke 133 the spring tends to move the piston rod 28 and the slide 27 in the forward direction.

When the slide 27 and the associated parts are in their rearward position, as shown in Fig. 3, the rod 131 and the spring 132 may be readily removed by first forcing the rod forward far enough to free it from the opening in the plate 130. Then the rear end of the rod can be lowered and the rod and the spring can be withdrawn in the rearward direction. In order that the slide 27 and the piston rod 28 may be withdrawn from the gun at the rear, in the manner already described, the yoke 133 is so constructed that it may be readily detached from the rod 28. As shown in Figs. 4 and 5, the yoke 133 has two ears 133a, 133a which embrace the rod 28 and are formed with notches for receiving a transverse pin 135 forming diametrically opposed lateral projections on the rod. After the rod 131 and the spring 132 have been removed as already described, the yoke can be turned to the position shown in Fig. 5 and then it can be pushed forward and thus completely detached from the piston rod by these sequential movements of rotation and translation.

The firing mechanism to which the invention more particularly relates will now be described.

The slide 27 is formed with an upstanding portion 138 which acts as a hammer to directly engage the enlarged rear end of the firing pin 139, as clearly shown in Fig. 2. Thus firing is automatically effected as soon as the breech bolt and associated parts reach their forward positions, there being no separate and independently movable hammer. For retaining the slide 27 in its rearward position there is provided a sear 140 biased by a spring to operative position, that is, in engagement with a notch 27a in the slide and the sear is operable by a trigger 141 on the rear plate of the casing, which serves to move the sear to an inoperative position, that is, out of engagement with the slide. The sear 140 has a rearward extension 140a which is adapted to be engaged by a forward extension 141a on the trigger. The sear 140 is pivoted at 142 to a bottom plate 143. 5

In addition to the main sear 140 there is provided an auxiliary sear 144 also carried by the plate 143, this auxiliary sear being also engageable with the notch 27a. These two sears are preferably coaxially mounted at 142, but the sear 144 has an elongated slot 144a which permits it to move longitudinally through a limited distance for a purpose to be presently set forth. To hold the sear 144 in engagement with the breech mechanism there is provided sear retaining mechanism. This mechanism may also be utilized as sear releasing mechanism as will be apparent hereinafter. A spring 145 tends to hold the sear 144 in its rearward position, as shown in Fig. 9, and the said sear is further held by a forward projecting finger 144b thereon which engages a shoulder on an oscillatory abutment member 146 carried by a pivot pin 147. The member 146 may also have formed thereon the sear releasing cam surface as shown. Connected with the abutment member 146 is a forward projecting finger 148 which under certain conditions is obstructed by a laterally projecting arm of a bell crank or obstruction member 149 vertically pivoted at 150. A spring 151 serves to bias the member 149 in the clockwise direction and to tend to hold it in the position shown in Fig. 7. With the parts in the positions shown in Fig. 7 the member 149 prevents the finger 148 and the abutment member 146 from turning and the abutment member holds the sear 144 in its rearward position. The sear by reason of its engagement with the slide holds the said slide and its associated parts in the rearward positions, as shown in Fig. 3. 10

In order to reduce the rate of automatic fire when desired, fire retarding mechanism may be provided for controlling the auxiliary sear 144. Longitudinally slidably in a recess in the plate 143 is a slide 152 comprising a body including an arm which is biased for movement toward the rear by means of a spring 153 carried by a guide rod 154. The slide 152 is provided with an upward projecting stud 155 which projects into a slot 27b in the bottom of the slide 27. When the slide 27 is in its rearward position, as shown in Fig. 3, the slide 152 is held by the spring 153 in its rearward position, as shown in Fig. 6; but when the slide 27 is in its forward position, as shown in Fig. 2, the rear end wall of the slot 27b is in engagement with the stud 155 and the slide 152 is also in its forward position, as shown in Fig. 7. 15

Escapement means may be provided for retarding the speed of movement of the slide 152 to sear releasing position. Mounted on a vertical pivot pin 156 carried by the plate 143 is a ratchet wheel 157 and an escapement wheel 158, these two wheels being connected together for movement in unison. Mounted on a pivot pin 159 is an escapement weight 160 having teeth thereon which engage the teeth on the wheel 158. The teeth on the escapement weight are so related to the teeth on the wheel that the weight is forced to oscillate as the wheel is turned, thus the weight offers resistance to the turning of the wheel. 20

Pivotedly connected at 161 with the slide 152 is a ratchet arm 162 which is biased for movement in the clockwise direction by means of a spring 163. The ratchet arm 162 has teeth thereon adapted to engage with the teeth of the ratchet wheel 157, the teeth being held in engagement by reason of the bias of the spring 163. When the slide 152 is moved forward by the slide 21 to the position shown in Fig. 7 the ratchet arm 162 moves with it, but the teeth thereof may snap over the teeth of the ratchet wheel 157 without causing any rotation of the said wheel. 25

When the slide 27 is moved rearward by the action of the gases to operate the gun mechanism, the slide 152 does not move in unison with it, but, on the contrary, moves at a much slower speed, its movement being resisted and retarded by the engagement of the ratchet arm 162 with the ratchet wheel 157. During this rearward movement of the slide 152, the slide 27 and associated parts are held by the sear 144, these parts being so held even though the trigger 141 has been pressed so as to maintain the sear 140 in its disengaging position. 30

When the slide 152 reaches its extreme rearward position the end portion 152a of the said slide engages the rearward extending arm of the member 149 to turn the said member in the counter-clockwise direction to the position shown in Fig. 6. With the member 149 in this position the finger 148 is no longer obstructed and the abutment member 146 is free to turn in the clockwise direction. Still assuming that the sear 140 has been held in its disengaging position by means of the trigger 141, the pressure exerted by the action spring 132 will move the slide 27 forward, carrying the sear 144 with it and turning the abutment member 146. The cam surface on the member 146 in moving forces the sear 144 to move to the position shown in Fig. 8; and the sear in so moving releases the slide 27, permitting it to move forward and effect the firing of the cartridge in the manner already described. Fig. 8 shows the slide 27 in the position at which it is released by the sear 144, the slide being entirely free to move forward. As the slide 27 moves forward the slide 152 is also moved forward, and the member 149 is restored by the spring 151 to its obstructing position, as shown in Fig. 7. 35

Preferably there is a cam 164 connected with the abutment member 146. When the parts are in the position shown in Fig. 8, the cam (although not shown in this figure) projects upward into the path of movement of the operating slide 27. When the slide again moves rearward it engages the cam 164 to positively move the abutment member 146 and the sear 144 to their slide engaging positions, as shown in Fig. 9. 40

It will be observed that when the retarding mechanism is used the main sear 140 normally has no control of the firing except to start and stop it. The rate of fire is controlled entirely by the auxiliary sear 144, the forward movement of the slide 27 being delayed for a short interval 45

75

following each shot and the rate of fire being correspondingly reduced.

In order that the retarding mechanism may be rendered inoperative when not required, there are provided certain additional parts which will now be described. Longitudinally movable on the plate 143 is a slide 165 which is connected by means of a stud 166 with a slide 167 longitudinally movable along guideways on the bottom of the plate 143. The slide 167 is provided with a finger piece 167^a by means of which it may be moved, and the slide further has a manually releasable latch 168 by means of which it may be held either in its rearward position, as shown in Figs. 8 and 9, or in its forward position, as shown in Figs. 10 to 12.

The slide 165 when in its rearward position is entirely ineffective, but when moved to its forward position the front end thereof engages the slide 152 to hold it in forward position, as shown in Figs. 10 to 12. The slide 165 is provided with an upward projection 165^a which engages a cam surface 144^c on the sear 144 to move it to a disengaged position, as shown in Figs. 11 and 12. With the parts in the positions shown in Figs. 10 to 12 the retarding mechanism is entirely ineffective and the action of the gun is exactly the same as if the said mechanism were not provided.

When a sear such as the sear 140 is controlled entirely manually, there is the possibility that, when the operating slide is in its rearward position, the sear may be in intermediate position where it is uncertain whether it will or will not sufficiently engage the slide to hold it. The sear 35 may momentarily catch and then by reason of vibration or otherwise may release the slide and cause the firing of an unexpected or unfired shot. To avoid these difficulties it may be preferable to provide a latch or retainer for holding the sear 40 in its fully disengaged position until the trigger is substantially fully released, the sear being then permitted to snap quickly to the position in which it fully engages the slide.

Referring particularly to Figs. 6, 8, 9, 13 and 14, it will be observed that there is provided a sear retainer 169 pivoted at 170 to a block 171. This block is suitably secured in the recess in the plate 143 at the rear thereof and at the left side. A spring 172 biases the retainer 169 for movement 50 in the counterclockwise direction. When the sear 140 is in its fully depressed position, as shown in Fig. 14, the retainer 169 projects over the edge of the rearward extension 141^a on the sear and holds the sear in its depressed position.

When the trigger 141 is released the forward extension 141^a thereof may move upward at least to the position shown in Fig. 14, without permitting any corresponding upward movement of the sear. When the position shown in Fig. 14 is 60 reached, the extension 141^a engages a cam surface 169^a on the retainer and further upward movement of the extension 141^a causes the retainer to swing toward the left, thus releasing the sear and permitting it to move suddenly upward to its engaging position, as shown in Fig. 9.

As already stated, the trigger 141 is carried by the rear casing plate which is removable in the upward direction and replaceable in the downward direction. In order that the sear retainer 70 169 may not interfere with the downward movement of the rearward extension 141^a on the trigger, it is provided with a cam surface 169^b which is engaged by the said extension as it moves downward. This cam surface 169^b serves to move the

retainer toward the left sufficiently to let the trigger extension 141^a move past it.

While I have shown the retarding mechanism in combination with a particular firing mechanism, it will be understood that I do not necessarily so limit myself and the said retarding mechanism may be combined with some other firing mechanism, such as shown in Figs. 2 and 3 of my said copending application Serial No. 719,862.

What I claim is:

1. In an automatic firearm including a sear, fire retarding mechanism comprising in combination a slidable body, an arm on said body slidable therewith to and from a sear releasing position, a second arm on the body, means for biasing the body to sear releasing position, and an escapement means cooperating with the second arm for retarding the speed of movement of the body to sear releasing position.

2. In an automatic firearm including a sear, fire retarding mechanism comprising in combination a slidable body, an arm on said body slidable therewith to and from a sear releasing position, a second arm pivoted to the body and extending 25 in the same direction as the first arm and biased toward the latter, means for biasing the body to sear releasing position, and an escapement means positioned between the two arms and co-operating with the second arm for retarding the 30 speed of movement of the body to sear releasing position.

3. In an automatic firearm, the combination of a sear, sear retaining mechanism movable to and from a sear releasing position, sear control means, 35 means biasing said sear control means toward a position in which it engages and moves said sear retaining mechanism to its sear releasing position, and retarding mechanism connected to the sear control means for regulating its speed of 40 movement to sear retaining mechanism engaging position.

4. In an automatic firearm, the combination of a breech casing, a biased breech member, a sear mounted on the casing for pivotal and sliding movement to and from operative engagement with the breech member, a sear retaining and releasing member having a projection thereon engaging the sear to hold the sear in said operative engagement or to permit the sear to move the 50 member and having a cam surface thereon for engagement with the sear to pivotally move the latter to an inoperative position upon movement of the member by the sear, an obstruction member engageable with the sear retaining and releasing member to prevent movement of the same, 55 and control mechanism engageable with the obstruction member to move it out of engagement with the sear retaining and releasing member whereby the biased breech member can slide 60 the sear to cause the cam surface on the sear retaining and releasing member to pivotally move the sear out of engagement with the breech member.

5. In an automatic firearm, the combination 65 of a sear, a trigger for releasing said sear, a second sear, sear control mechanism for said second sear, means for moving the sear control mechanism to a sear releasing position, retarding means associated with said mechanism for regulating its 70 speed of movement to sear releasing position, and means separate from said trigger for positively holding said second sear in an inoperative position while the firearm is being repeatedly fired in a fully automatic manner.

6. In an automatic firearm, the combination of a sear, sear control mechanism, means for moving the sear control mechanism to a sear releasing position, retarding means associated with said mechanism for regulating its speed of movement to sear releasing position, means for positively holding the sear in an inoperative position while the firearm is being repeatedly fired in a fully automatic manner, and means for holding the sear control mechanism immovable.

7. In an automatic firearm, the combination of a sear, mechanism for effecting and controlling movement of the sear to an inoperative position, said mechanism including means for delaying the movement of the sear to said inoperative position, movable means for selectively rendering the delaying means inoperative, and additional means for effecting movement of the sear to its inoperative position and for positively holding it in said position, said additional means being simultaneously movable with the said movable means.

8. In an automatic firearm, the combination of a sear, mechanism for effecting and controlling movement of the sear to an inoperative position, said mechanism including means for delaying the movement of the sear to said inoperative position, and a single member for rendering the delaying means inoperative and for effecting movement of the sear to its inoperative position and for positively holding it in said position.

9. In combination in an automatic firearm, breech mechanism automatically movable rearward upon firing and biased for automatic return movement to its forward position, firing means automatically operable when the breech mechanism reaches its forward position, a sear biased toward a position for engaging the breech mechanism to hold it in its rearward position, mechanism including a longitudinally movable slide and serving when the slide is in its rearward position to cause the said sear to disengage the breech mechanism, means for causing the slide to be moved forward in unison with the breech mechanism, means independent of the breech mechanism for moving the slide rearward immediately after its said forward movement, and means for retarding the rearward movement of the slide so that there is a predetermined interval between the automatic engagement of the sear with the breech mechanism and the disengagement thereof effected by the slide.

10. In combination in an automatic firearm, breech mechanism automatically movable rearward upon firing and biased for automatic movement to its forward position, firing means automatically operable when the breech mechanism reaches its forward position, a sear biased toward a position for engaging the breech mechanism to hold it in its rearward position, a movable member serving in one position to obstruct disengagement of the sear, mechanism including a longitudinally movable slide and serving when the slide is in its rearward position to move the said movable member out of its obstructing position so as to enable the sear to disengage the breech mechanism, means for causing the slide to be moved forward in unison with the breech mechanism, means independent of the breech mechanism for moving the slide rearward immediately after its said forward movement, and means for retarding the rearward movement of the slide so that there is a predetermined interval between the automatic engagement of the sear with the breech mechanism and the disengagement thereof en-

abled by the movement of the obstructing member.

11. In combination in an automatic firearm, breech mechanism automatically movable rearward upon firing and biased for automatic return movement to its forward position, firing means automatically operable when the breech mechanism reaches its forward position, a sear biased toward a position for engaging the breech mechanism to hold it in its rearward position, a movable abutment member for normally engaging the sear to prevent disengaging movement thereof, a movable member serving in one position to obstruct movement of the abutment member, a longitudinally movable slide serving in its rearward position to move the said obstructing member out of its obstructing position so as to enable the abutment member to move and permit the sear to disengage the breech mechanism, means for causing the slide to be moved forward in unison with the breech mechanism, means independent of the breech mechanism for moving the slide rearward immediately after its said forward movement, and means for retarding the rearward movement of the slide so that there is a predetermined interval between the automatic engagement of the sear with the breech mechanism and the disengagement thereof enabled by the movement of the obstructing member and of the abutment member.

12. In combination in an automatic firearm, breech mechanism automatically movable rearward upon firing and biased for automatic return movement to its forward position, firing means automatically operable when the breech mechanism reaches its forward position, a sear biased toward a position for engaging the breech mechanism to hold it in its rearward position, a movable abutment member for engaging the sear to prevent disengaging movement thereof, a longitudinally movable slide serving in its rearward position to enable the abutment member to move and permit the sear to disengage the breech mechanism, means for causing the slide to be moved forward in unison with the breech mechanism, means independent of the breech mechanism for moving the slide rearward immediately after its said forward movement, means for retarding the rearward movement of the slide so that there is a predetermined interval between the automatic engagement of the sear with the breech mechanism and the disengagement thereof enabled by the movement of the abutment member, and cam means associated with the abutment member and the breech mechanism for causing the latter to positively return the former to its sear engaging position.

13. In combination in an automatic firearm, breech mechanism automatically movable rearward upon firing and biased for automatic return movement to its forward position, firing means automatically operable when the breech mechanism reaches its forward position, a sear biased toward a position for engaging the breech mechanism to hold it in its rearward position, mechanism including a longitudinally movable sear controlling slide and serving when the slide is in its rearward position to cause the said sear to disengage the breech mechanism, means for causing the slide to be moved forward in unison with the breech mechanism, means independent of the breech mechanism for moving the slide rearward immediately after its said forward movement, means for retarding the rearward movement of the slide so that there is a predetermined interval

between the automatic engagement of the sear with the breech mechanism and the disengagement thereof effected by the slide, and a single manually operable means for moving the sear to a disengaging position and for moving the said sear controlling slide to its forward position.

14. In combination in an automatic firearm, breech mechanism automatically movable rearward upon firing and biased for automatic return movement to its forward position, firing means automatically operable when the breech mechanism reaches its forward position, a sear biased toward a position for engaging the breech mechanism to hold it in its rearward position, mechanism including a longitudinally movable sear controlling slide and serving when the slide is in its rearward position to cause the said sear to disengage the breech mechanism, means for causing the slide to be moved forward in unison with the breech mechanism, means independent of the breech mechanism for moving the slide rearward immediately after its said forward movement, means for retarding the rearward movement of the slide so that there is a predetermined interval between the automatic engagement of the sear with the breech mechanism and the disengagement thereof effected by the slide, and a manually operable longitudinally movable slide serving when moved forward to engage the sear controlling slide to move it forward and also to engage the sear to move it to a disengaging position.

15. In combination in an automatic firearm, breech mechanism automatically movable rearward upon firing and biased for automatic return movement to its forward position, firing means automatically operable when the breech mechanism reaches its forward position, a main sear and an auxiliary sear each biased toward a position for engaging the breech mechanism to hold it in its rearward position, a manually operable trigger for moving the main sear to its disengaging position, mechanism including a longitudinally movable slide and serving when the slide is in its rearward position to cause the said auxiliary sear to disengage the breech mechanism, means for causing the slide to be moved forward in unison with the breech mechanism, means independent of the breech mechanism for moving the slide rearward immediately after its said forward movement, and means for retarding the rearward movement of the slide so that there is a predetermined interval between the automatic engagement of the auxiliary sear with the breech mechanism and the disengagement thereof effected by the slide.

16. Sear and trigger mechanism comprising in combination a sear biased to operative position, a trigger engageable with the sear to move the latter to inoperative position, and a sear retainer engageable with the sear to hold the same in its inoperative position and also being engageable by the trigger upon movement of the latter toward non-firing position to be moved thereby to a sear releasing position, the trigger being movable to a predetermined extent before it moves the sear retainer to sear releasing position thereby permitting the sear to move with a snap action free from restraint by the trigger upon disengagement of the sear and sear retainer.

17. Sear and trigger mechanism comprising in combination a sear biased to operative position, a trigger engageable with the sear to move the lat-

ter to inoperative position, and a pivoted sear retainer engageable with the sear to hold the same in its inoperative position and having a cam surface engageable by the trigger upon movement of the latter towards its non-firing position to be moved thereby to a sear releasing position, the trigger being movable to a predetermined extent before it moves the sear retainer to sear releasing position thereby permitting the sear to move with a snap action free from restraint by the trigger upon disengagement of the sear and sear retainer.

18. Sear and trigger mechanism comprising in combination a sear biased to operative position, means including a trigger operable to move the sear to its inoperative position, and additional means including a sear retainer engageable with the sear to hold the same in its inoperative position and also being engageable by said first mentioned means upon movement of the same toward non-firing position to be moved thereby to a sear releasing position, the trigger being movable to a predetermined extent before movement of the sear retainer to sear releasing position is effected thereby permitting the sear to move with a snap action free from restraint by the trigger upon disengagement of the sear and sear retainer.

19. In an automatic firearm, the combination of breech mechanism automatically movable rearward upon firing and biased for automatic return movement to its forward position, firing means automatically operable when the breech mechanism reaches its forward position, a sear biased toward a position for engaging the breech mechanism to hold it in its rearward position, a trigger for moving the sear to disengage it from the breech mechanism, a sear retainer biased to a position in which it holds the sear in its disengaged position, and means associated with the sear retainer and the trigger for automatically moving the retainer so as to release the sear and permit it to move with a snap action to its engaging position when the trigger is returned to its non-firing position.

20. In an automatic firearm, the combination of a breech casing, a rear plate for the breech casing removable in the upward direction and replaceable in the downward direction, breech mechanism in the casing automatically movable rearward upon firing and biased for automatic return movement to its forward position, firing means automatically operable when the breech mechanism reaches its forward position, a sear in the casing adjacent the rear plate and biased upward toward a position for engaging the breech mechanism to hold it in its rearward position, a trigger on the rear plate for moving the sear downward to disengage it from the breech mechanism, a sear retainer biased to a position in which it holds the sear in its lower disengaged position, means associated with the sear retainer and the trigger for automatically moving the retainer so as to release the sear and permit it to move upward with a snap action to its engaging position when the trigger is returned upward to its non-firing position, and cam means associated with the sear retainer and the trigger for moving the retainer laterally out of the path of the trigger when the rear plate and trigger are moved downward during replacement.
